HARLAN S. GANO, OF WILKINSBURG, AND MATSON C. TERRY, OF PHILADELPHIA, PENNSYLVANIA, ASSIGNORS TO WESTINGHOUSE ELECTRIC AND MANUFACTURING COMPANY, A CORPORATION OF PENNSYLVANIA.

DEVICE FOR CONTROLLING THE FLOW OF FLUIDS.

Application filed September 12, 1923. Serial No. 662,301.

To all whom it may concern:

Be it known that we, HARLAN S. GANO and MATSON C. TERRY, citizens of the United States, and residents of Wilkinsburg and 5 Philadelphia, respectively, in the counties of Allegheny and Philadelphia, respectively, and State of Pennsylvania, have invented a new and useful Improvement in Devices for controlling the Flow of Fluids, of which 10 the following is a specification.

Our invention relates to devices for controlling the flow of fluids in response to temperature and pressure conditions and it has for an object to provide apparatus of 15 the character designated which shall be of simple and rugged construction, and which shall exercise a very sensitive control over the flow of the fluid in response, not only to the variations in temperature and pressure 20 prevailing within an apparatus to which the fluid is delivered, but also in response to variations in the temperature and pressure of the fluid itself.

These and other objects, which will be 25 made apparent throughout the further description of the invention, may be obtained by the employment of apparatus herein-after described and illustrated in the accompanying drawing in which the single figure 30 is a view in sectional elevation of one form of device in which our invention may be practiced.

Our device may be readily employed, for 35 example, to control the flow of cooling water to a condenser. By its use, the flow of the cooling water is controlled, not only in response to the temperature and pressure of the controlling medium but also in response to variations in the temperature of 40 the water prior to its entrance into the condenser. In this manner, a perfect heat balance may be maintained at all times and a steady, uniform performance of the apparatus effected, resulting in a substantial increase in efficiency.

Referring to the drawing for a more detailed description of our invention, we show 45 a casing 10 having provided therein a fluid inlet port 11 and a fluid outlet port 12. Secured to the casing 10 is a cover plate 13 having provided therein a port 14 for connecting to the apparatus to which the fluid is to be delivered. Interposed between the casing 10 and the cover plate 13 is a bi-

metallic diaphragm consisting of two flexible metallic diaphragms 15 and 16 composed of materials having relatively different coefficients of expansion such as, for example, steel and brass. The two materials may be welded or rolled together. The diaphragm 15 having the lesser coefficient of expansion may be arranged adjacent to the cover plate 13 while the diaphragm 16 having the greater coefficient of expansion may be arranged adjacent to the casing 10. The edges of the bi-metallic diaphragm are held rigidly in place between the casing 10 and the cover plate 13 by bolts 17 which, together with the gaskets 18 and 19, make a fluid-tight connecting joint between the casing 70 and the cover plate.

Provided in the casing 10 and disposed between the fluid inlet and outlet ports 11 and 12 is a dividing wall 21 having provided therein a conical valve seat 22. Associated therewith is a valve 23 which is secured to a spindle 24 by means of a nut 25. The nut 25 engages a threaded portion 26 of the spindle. The spindle 24 is maintained in axial alignment by a bearing 27 80 and is provided with a palm 28 which bears against the diaphragm. The bearing 27 is secured by means of ribs 29 to the casing 10. The valve 23 is biased to a closed position by a spring 31, which is maintained under 85 compression by the nut 25 and the adjusting nut 32. The adjusting nut 32 engages screw threads 33 provided in the casing 10, by means of which the location of the adjusting nut 32 may be altered and the compressive force of the spring 31 regulated. The lower end of the casing 10 is closed by 90 means of a plug 34 which engages the threads 33 and makes a fluid-tight joint with the casing by means of a suitable gasket 35. 95

The operation of the above embodiment of our invention is as follows: The inlet 11 is connected with a source of fluid under pressure, and the outlet 12 is connected to the apparatus to which it is desired to convey the fluid. The port 14 may be connected to a chamber of the apparatus receiving the fluid and in which a medium having a variable temperature and pressure prevails in accordance with which it is desired to 100 control the flow of the fluid.

Upon the fluid entering the lower compartment of the casing 10 by means of the

inlet port 11, the compartment becomes filled and pressure is exerted upon the valve 23 tending to hold it closed. Upon a predetermined increase in the temperature or pressure of the medium in contact with the upper surface of the bi-metallic diaphragm, the latter will act to move the valve 23 from its seat 22 to permit fluid to enter the upper compartment of the casing 10 and to flow through the outlet port 12 to the apparatus. The pressure of the fluid upon entering the upper compartment of the casing 10 is exerted upon the lower surface of the bi-metallic diaphragm and tends to slightly reduce the extent of the initial valve opening. The temperature of the fluid also affects the diaphragm and causes a deflection thereof, the extent and direction of which depend upon the difference in temperature of the fluid with respect to that of the medium acting upon the upper surface of the diaphragm. In this manner, the controlling device makes immediate response to changes in the temperature of the controlled fluid, thereby insuring a highly uniform and efficient performance of the controlled apparatus at all times.

Should the pressure or temperature of the fluid acting upon the upper surface of the bi-metallic diaphragm become less, the latter will retract and partly close the valve, and, upon sufficient reduction in temperature or pressure, will shut off the supply of fluid entirely. If, during the flow of the fluid, the temperature thereof should change, this change will immediately react upon the diaphragm to alter the position of the valve.

Should it be desired at any time to slightly alter the initial temperature or pressure required to open the valve, this may be readily accomplished by removing the plug 34 and screwing upwardly or downwardly the adjusting nut 32.

Apparatus of the character disclosed herein is especially adapted for use in connection with compression refrigerators of the household type which employ water as a condensing medium, and in which our apparatus may be employed to control the flow of the water through the condensing coils in response to the temperature and pressure prevailing within the condensing chamber and in response to changes in the temperature and pressure of the cooling water. As the amount of water employed is a rather important item in the operating costs of apparatus of this type, very careful flow regulation is highly desirable. We have found, that with the use of the apparatus heretofore described, extremely sensitive regulation of the amount of water entering the refrigerator may be obtained without care or attention for almost indefinite periods of time.

While we have shown our invention in but one form, it will be obvious to those skilled

in the art that it is not so limited, but is susceptible of various other changes and modifications, without departing from the spirit thereof, and we desire, therefore, that only such limitations shall be placed thereupon as are imposed by the prior art or as are specifically set forth in the appended claims.

What we claim is:

1. In a device for controlling the flow of fluid, the combination of a flexible diaphragm composed of materials having relatively different coefficients of expansion, means for subjecting that portion of the diaphragm having the greater coefficient of expansion to the temperature of a fluid, means for subjecting that portion of the diaphragm having the lesser coefficient of expansion to the temperature of a medium, and means for controlling the flow of the fluid in response to movements of the diaphragm.

2. In a device for controlling the flow of fluid, the combination of a flexible bi-metallic diaphragm, means for subjecting one side of said diaphragm to the temperature and pressure of a controlling medium, means for subjecting the opposite side of said diaphragm to the temperature and pressure of a fluid, and means for controlling the flow of said fluid in response to movements of the diaphragm.

3. In a device for controlling the flow of fluid, the combination of a casing, inlet and outlet means for the passage of a fluid provided in the casing, valve means for controlling the flow of the fluid through the casing, and a bi-metallic diaphragm for actuating said valve means, said bi-metallic diaphragm being so arranged in the casing as to be subject on one side to the temperature and pressure of the fluid and upon its opposite side to the temperature and pressure of an extraneous medium, whereby the flow of the fluid is controlled in response to variations in the temperature and pressure of said fluid and to the temperature and pressure of said medium.

4. In a device for controlling the flow of fluid, the combination of a casing having a valve seat provided therein, a valve associated with said valve seat, fluid inlet and outlet means provided in the casing on oppositely disposed sides of the valve seat, and a bi-metallic diaphragm disposed on the outlet side of the valve for actuating the same, said diaphragm being subject upon its one side to the temperature and pressure of the fluid passing through the casing and upon its opposite side to the temperature and pressure of an extraneous medium.

5. In a device for controlling the flow of fluid, the combination of a casing, a bi-metallic diaphragm disposed therein, means provided within the casing for subjecting one side of said diaphragm to the tempera-

- ture and pressure of an extraneous medium, fluid inlet and outlet means so arranged within the casing as to subject the opposite side of the diaphragm to the temperature and pressure of the fluid, valve means interposed in the path of said fluid, and connecting means between the bi-metallic diaphragm and the valve means for actuating the latter in response to movements in the diaphragm.
- 6 5. In a device for controlling the flow of fluid, the combination of a casing, inlet and outlet means for the passage of a fluid provided in the casing, valve means disposed in the path of said fluid, a bi-metallic dia-
phragm for actuating the valve means, said bi-metallic diaphragm being subject upon one portion to the temperature and pressure of the fluid passing through the casing and upon a second portion to the temperature and pressure of an extraneous medium, and means for biasing said valve to a closed position.
- 10 6. In a device for controlling the flow of fluid, the combination of a casing, inlet and outlet means for the passage of a fluid provided in the casing, valve means disposed in the path of the fluid, a bi-metallic dia-
phragm for actuating the valve means, said bi-metallic diaphragm being subject upon one side to the temperature and pressure of the fluid passing through the casing and upon its opposite side to the temperature and pressure of an extraneous medium, and adjustable means for biasing said valve to a closed position.
- 15 7. In a device for controlling the flow of fluid, the combination of a casing, fluid inlet and outlet means provided in the casing, a valve for controlling the flow of fluid through the casing, a bimetallic diaphragm movable in response to both the temperature and pressure of the fluid for actuating the valve, and means for biasing the valve to a closed position.
- 20 8. In a device for controlling the flow of fluid, the combination of a casing, a fluid inlet and an outlet provided in the casing, a valve for controlling the flow of fluid through the casing, and a bimetallic dia-
phragm subject to the temperature and pressure of the fluid for actuating the valve.
- 25 9. In a device for controlling the flow of fluid, the combination of a casing, a fluid inlet and an outlet provided in the casing, a valve for controlling the flow of fluid through the casing, and a bimetallic dia-
phragm subject to the temperature and pressure of the entering fluid for actuating the valve.
- 30 10. In a device for controlling the flow of fluid, the combination of a casing, a fluid inlet and an outlet provided in the casing, a valve for controlling the flow of fluid through the casing, and a bimetallic dia-
phragm subject on one side to the temperature and pressure of the entering fluid for controlling the movements of the valve.
- 35 11. In a device for controlling the flow of fluid, the combination of a casing, fluid inlet and outlet means provided in the casing, a valve for controlling the flow of fluid through the casing, a bimetallic diaphragm movable in response to both the temperature and pressure of the fluid for actuating the valve, and means for biasing the valve to a closed position.

In testimony whereof, we have hereunto subscribed our names this 8th day of August, 1923.

HARLAN S. GANO.
MATSON C. TERRY.
